UNITED STATES PATENT OFFICE.

FREDERICK W. HENNINGER, OF DETROIT, MICHIGAN.

MACHINE FOR CLEANING, STRAIGHTENING, AND REINSULATING OLD WIRE.

SPECIFICATION forming part of Letters Patent No. 717,574, dated January 6, 1903.

Application filed June 18, 1902. Serial No. 111,518. (No model.)

To all whom it may concern:

Be it known that I, FREDERICK W. HENNINGER, a citizen of the United States, residing at Detroit, county of Wayne, State of Michigan, have invented a certain new and useful Improvement in Machines for Cleaning, Straightening, and Reinsulating Old Wire; and I declare the following to be a full, clear, and exact description of the invention, such as will enable others skilled in the art to which it pertains to make and use the same, reference being had to the accompanying drawings, which form a part of this specification.

15 My invention relates to an improvement in machines for cleaning, straightening, and re-insulating old wire, shown in the accompanying drawings and more particularly described in the following specification and claims.

20 Referring to the drawings, Figure 1 is a perspective view showing the wire in the act of being cleaned of the old insulation, straightened, and wound with new insulating-tape. Fig. 2 is a sectional view through the tape-reel. Fig. 3 is a perspective view of one of the cutting-disks composing one of the rolls for freeing the wire of the old insulation.

25 Referring to the letters of reference shown in the drawings, A A are standards designed 30 to support the frame B. At one end of the frame B is journaled the roll D, composed of a series of cutting-disks d, assembled together on the shaft. E is another roll composed of a similar series of cutting-disks e, but preferably of smaller diameter, mounted on the bell-crank lever F, pivoted at f to the frame B and adapted to come in close proximity to the cutting-disks of the roll D. The forward end of the bell-crank lever is sleeved to receive a screw-threaded bolt G, provided with a thumb-nut g', bearing on the lugs b² of the frame.

35 g is a spring coiled around the bolt G and adapted to force the roll E into contact with the old insulation on the wire H.

40 It is obvious that the pressure of the cutting-disks may be increased or diminished by adjusting the thumb-nut g'.

45 I is a coil-spring designed to free the wire of the old insulation after the same has been cut in its passage through the rolls E and D. This spring is supported in the cup-shaped

casting i i, the lower of which may be integral with the frame B and the upper bolted thereto.

55

I' is a screw-threaded bolt provided on the inside of the casting i with a suitable disk (not shown) to engage the spring and designed to increase or decrease the tension.

5 My invention relates to an improvement in machines for cleaning, straightening, and re-insulating old wire, shown in the accompanying drawings and more particularly described in the following specification and claims.

60 J and J' are tension-rolls, J being provided with an adjusting-screw j. The bearing for the tension-roll J is sleeved within the depending lugs b³ of the frame to insure against displacement. The tension-roll J' is pivoted in the return-bend B' of the frame B.

65

K is a gear-case bolted to the frame B, inclosing a bevel-gear mounted on the shaft of the tension-roll J' and meshing with the gear L, inclosed within the gear-case K'.

70 M is a tape-reel supported on the angle-iron bolted to the gear L. This tape-reel is constructed with two disks m and m', the disk m' being rigidly engaged with the angle-iron, while the disk m is free to rotate on the shaft m². This shaft on the inside is provided with an enlarged head m⁶, and at the opposite end is screw-threaded to receive a milled thumb-nut m³. The shaft m² is square at m⁷ to insure it against rotation. Coiled around the bolt, between the angle-iron and the thumb-nut, is a spring m⁸, the tension of which is designed to bring the disks in frictional contact. I prefer, however, to insert between the disks m and m' a disk of paper or rubber m⁴ for increasing the friction and to relieve the metal surfaces from wear. Secured to the disk m are spring-arms m⁵ to receive the roll of tape N.

75

80 To fix the frame at any desired angle when once adjusted, I provide an arc-shaped slot a in one or both of the standards A. Through this passes a bolt which engages the frame B. The shank of the hand-wheel is designed to impinge against the standard and hold the frame at any angle desired within the compass of the quadrant.

85

85 The operation of the device is as follows: The wire H as it is unwound from the old field-coil passes under the roll D' and up between the cutting-disks of the rolls E and D, where the old insulation is shredded and otherwise disintegrated. After passing around the roll D it is fed forward to and through the scraper I, where the old insulation not previously re-

90

95

moved is cleared from the wire. The bare wire is then fed forward between the tension-rolls J and J', which, with the other rolls and scraper, straighten the wire, taking out any 5 kinks that may be found in it. The friction of the wire on the roll J', due to its passage between the tension-rolls, rotates the gear housed within the case K, and it being in mesh with the gear L carries the spool of tape 10 around the wire as it is fed out to the new field, and as it rotates it unrolls the tape and winds it upon the wire. The tension governing the unwinding of the tape may be regulated by the thumb-screw m^3 .

15 Having thus described my invention, what I claim is—

1. In a machine for removing and restoring insulated wire, cutting-rolls adapted to receive the insulated wire between their cutting edges, means for removing the old insulation after being submitted to the action of the cutting-rolls and means for feeding the wire through the cutting-rolls, substantially as described.

25 2. In a machine for removing and restoring insulated wire, cutting-rolls adapted to receive the insulated wire, consisting of a series of disks provided with cutting edges assembled together and suitably mounted and 30 means for feeding the wire through said rolls, substantially as described.

3. In a machine for removing and restoring insulated wire, cutting-rolls adapted to receive the insulated wire between their cutting edges, one of said rolls mounted in a fixed bearing, the other in an adjustable bearing, the construction being such that the rolls are brought into cutting contact with the insulation on the wire as the wire is fed through, 35 substantially as described.

40 4. In a machine for removing and restoring insulated wire, cutting-rolls adapted to receive the insulated wire between their cutting edges, one of said rolls mounted on one

end of a swinging lever, a bolt sleeved in the 45 opposite end of said lever and having a sleeved engagement with the frame, a spring adapted to bring the roll in cutting contact with the insulation on the wire and means for increasing or diminishing the pressure of the 50 cutters, substantially as described.

5. In a machine for removing and restoring insulated wire, a scraper for removing the old insulation consisting of a coiled spring 55 through which the wire travels suitably mounted in the frame and means for regulating the tension of the spring, substantially as described.

6. In a machine for removing and restoring insulated wire, tension-rolls through which 60 the wire travels in its passage through the machine, one of said rolls mounted in an adjustable bearing, a set-screw engaging said bearing for regulating the tension of the roll on the wire, a tension-roll acting in conjunction with the adjustable roll mounted on a shaft in a fixed bearing with a gear adapted to rotate the tape-reel around the wire, and said tape-reel, substantially as described.

7. In a machine for removing and restoring 70 insulated wire, a tape-reel consisting of a fixed and loose disk, means for holding the disks in frictional contact and a disk m^4 of paper interposed between said disks, substantially as described.

75 8. In a machine for removing and restoring insulated wire, a swinging frame mounted in suitable standards, standards slotted for the passage of a bolt designed to engage the frame whereby it may be held at the angle desired, 80 and the bolt and hand-wheel for setting the same, substantially as described.

In testimony whereof I sign this specification in the presence of two witnesses.

FREDERICK W. HENNINGER.
